DESIGN FOR A PLATE OR ANALOGOUS ARTICLE

Albert Reisner, New York, N. Y., assignor to
Heinrich & Winterling Inc., New York, N. Y.

Application May 26, 1934, Serial No. 51,925

Term of patent 7 years

To all whom it may concern:

Be it known that I, ALBERT REISNER, a citizen of the United States, residing at New York, in the county of New York and State of New York, have invented a new, original, and ornamental Design for Plates or Analogous Articles, of which the following is a specification, reference being had to the accompanying drawing, forming part thereof.

The figure is a plan view of a plate, showing my new design, only a portion of the border ornamentation being shown, it being understood that the remainder is a mere repeat thereof.

I claim:

The ornamental design for a plate or analogous article, as shown and described.

ALBERT REISNER.
